WATER MOTOR MACHINE

Filed July 29, 1931

Inventor:
Henry Placide

UNITED STATES PATENT OFFICE

HENRY PLACIDE, OF BALTIMORE, MARYLAND

WATER MOTOR MACHINE

Application filed July 29, 1931. Serial No. 553,868.

The invention relates generally to improvements in water motor machines, for connection with the water systems of buildings, or elsewhere, by making use of novel and peculiar arrangements for transmitting power by the pressure of water concentrated thru and from a jet onto a revolving rotary wheel, and particularly to improvements in machines wherein a jet of water under pressure 5 is directed tangentially against faces on the periphery of a rotary wheel, operated by a flow of water passing thru a casing containing same, for the grinding, buffing, sharpening, or other finishing, of tools, knives, blades, 10 or other implements or articles of all kinds. The arrangement constitutes a new and novel method for securing of a strong water pressure for operation of a water motor machine of the character elsewhere described herein, 15 and the compact size of the machine and arrangement for attachment to an ordinary faucet or spigot or hydrant is also a new and novel method for providing an efficient machine easily attachable to or removable from 20 the connection thru which the water or other fluid that operates the apparatus is supplied.

An object of the invention is to provide a machine based on the principal of water flowing thru a casing being concentrated and compressed thru one or more jets arranged at reverse angles within or at the end of the same casing for the purpose of producing forceful and swift continuous streams of water striking and impinging at right angles from the 25 inlet jet openings the peripheral blades of a rotary impeller wheel to be propelled thereby, arranged crosswise of the casing at right angles to the flow of water into, thru and out of the casing, in such manner as will impart maximum power to the rotary impeller wheel.

Another object is to provide a simplified and improved novel housing structure and arrangement for water motor machines 35 whereby maximum efficiency may be obtained, and size and weight of the machine reduced to a minimum.

Another object is to provide a compact and efficient machine of light weight which may be readily attached to any standard faucet,

spigot or hydrant, or other water connection and used for the grinding, buffing, sharpening, or other finishing, of tools, knives, blades, or other implements or articles of all kinds, or other purposes.

Another object is to provide effective and simplified means for holding the machine to a faucet, spigot or hydrant.

Other objects will appear in the following description.

The drawing illustrates the preferred embodiment of my invention as reduced to practice but as conditions concurrent with use of the device will necessarily vary it is to be understood that various minor changes in detail of construction, proportion or arrangement of parts may be resorted to when desired without forfeiting any of the advantages of my invention as described herein.

In the accompanying drawing—

Figure 1 is a front view of one form of the device shown applied to a faucet or spigot by means of a connection collar and set screw.

Figure 2 is an enlarged longitudinal section on the line 5—5 of Figure 6 thru the complete device.

Figure 3 is the same as Figures 1 and 5, only it is applied to a faucet or spigot having internal thread.

Figure 4 is a detail view of the impeller plate.

Figure 5 is a similar view to Figure 1, except it is applied to a faucet or spigot having external threads thereon.

Figure 6 is an enlarged section on the line 6—6 of Figure 2, looking down on the device.

Figure 7 is a section of a modification of the device.

Figure 8 is a view looking at the end of the wheel bushing, showing how the impeller wheel is held rigid thereto.

Corresponding and like parts are identified by the same reference characters throughout the several views.

Referring to the drawing—

In Figure 1, 1 designates the circular stock barrel in side elevation, extending thru the circular opening 2 in the housing 3 which fits over the seat 5 on the stock barrel 1 in rigid manner, the lower half of the housing 100

containing a larger circular opening broken away on each side 6 for the purpose of being pressed apart by pressure to allow each opposite side to be slipped over the end of the 5 housing barrel 7 and into the indented seat 8 thereon, where held rigidly in place by tension of the housing 3 itself against the housing barrel 7.

In Figure 2, within the housing 3 is shown 10 the rotary wheel 9 (of abrasive or other material) mounted on the wheel bushing 10 by means of melted lead or other material run between the outside of the wheel bushing 10 and the inside of the rotary wheel 9 and 15 melted into the circular seat 11 and cross seat 12 on the outside of the wheel bushing 10. The wheel bushing 10 fits over the stock barrel 1 (before housing 3 is mounted thereon) and has a seat 13 which rests lightly on 20 seat 14 of the stock barrel 1, which seat 14 acts as an axle for the wheel bushing seat 13 resting thereon, thereby enabling the wheel bushing 10 to revolve at high speed and in 25 forceful manner when water pressure is applied to the blades of the impeller wheel 15 thru the inlet jets 16 and 17 opening thru the impeller plate 18 as shown in Figures 2 and 4, or thru the solid bottom of the stock barrel 1, as shown in Figure 7.

30 In Figure 7, the inside of the wheel bushing 10 is shown widened out at the bottom for the purpose of providing thereon a seat 19 to act as a rest and holder of the ends of the blades of the impeller wheel 15 pressed firmly 35 against same and held tightly in place by the bottom edge of the wheel bushing 10 being pressed inward on each side of and over the bottom of the ends of the blades of the impeller wheel 15. The method of pressing the 40 bottom edge of the wheel bushing 10 over the blades of the impeller wheel 15 is shown fully in Figure 8.

While the stock barrel 1 in its preferred 45 form is to be a single piece made of solid metal bored out in the center for the purpose of constructing a proper casing, yet, for reasons of economy or otherwise, the stock barrel 1 may be made out of hollow tubing, in 50 which case it will be fitted inside with an impeller plate 18 (having the same inlet jets 16 and 17) as shown in Figure 4, to be pressed or 55 screwed down from the top of the stock barrel 1 and as shown in Figure 2 to rest on seat 20 on the inside of the stock barrel 1, spaced 60 a suitable distance from the bottom thereof.

The impeller wheel 15 may be made in 65 different styles, as in Figure 7, where cross section view shows the four blades of the impeller wheel 15 are the same width for their 70 full breadth for fitting directly under the stock barrel 1, or, as in Figure 2, where cross section view shows the four blades of the impeller wheel 15 are cut away on the upper 75 half for the purpose of allowing the center of the blades to protrude upward inside the

stock barrel 1 towards the impeller plate 18, spaced a suitable distance from the bottom thereof.

The concentrated water pressure injected 70 thru the inlet jets 16 and 17 strikes the blades of the impeller wheel 15 on a tangent at right angles with great force, thereby propelling in the opposite direction at high speed and in 75 forceful manner the impeller wheel 15 and wheel bushing 10 fastened thereto.

As shown in Figure 1, the connection collar 21 is used for connecting the machine to ordinary faucets or spigots, which do not have any threaded arrangements or other means of connection thereto, and is internally 80 threaded on the inside for the purpose of allowing the externally threaded end 22 of the stock barrel 1 to be screwed therein.

The connection collar 21 is internally 85 threaded all or part of the way, with a screw hole thru the top half thru which operates a set screw 23. The set screw 23 is screwed outward so that it does not protrude beyond the inside wall of the connection collar 21, which then allows the connection collar 21 to be 90 slipped up for about half its length over the outlet end of the faucet or spigot, whereupon the set screw 23 is screwed back in place, thereby holding the connection collar 21 to the faucet or spigot in firm and substantial 95 manner.

The connection collar 21 contains an internal washer, made of rubber or other suitable material, which rests midway in the connection collar 21 for compression between the 100 outlet end of the faucet or spigot and the inlet end of the externally threaded end 22 of the stock barrel 1 and makes a water tight joint when the externally threaded end 22 of the stock barrel 1 is screwed inwards in 105 the connection collar 21 against the outlet end of the faucet or spigot.

I claim:—

1. In a machine of the class described, a 110 stock barrel, an impeller plate provided with nozzles, a shoulder on the inside of the stock barrel for supporting the impeller plate, a wheel bushing provided with impeller blades, a shoulder on the outside of the stock barrel for supporting the wheel bushing in such a manner that the impeller blades carried thereby are in operative relation to the nozzles of the impeller plate.

2. A device as claimed in claim 1, including a circular seat on the wheel bushing for carrying a rotary tool operated by the impeller blades.

3. A device as claimed in claim 1, including a housing and a housing barrel carried by the stock barrel.

4. A device as claimed in claim 1, including a connection collar provided with suitable means such as screw threads, washer and set screw, for attaching the stock barrel to a 130 faucet.

5. In a machine of the class described, a stock barrel having a base portion provided with nozzles, a wheel bushing provided with impeller blades, a shoulder on the outside of
5 the stock barrel for supporting the wheel bushing in such a manner that the impeller blades carried thereby are in operative relation to the nozzles in the base portion of the stock barrel.
